UNITED STATES PATENT OFFICE.

EDWARD T. POTTER, OF NEWPORT, RHODE ISLAND.

MAGIC-LANTERN SLIDE.

SPECIFICATION forming part of Letters Patent No. 390,396, dated October 2, 1882.

Application filed December 14, 1887. Serial No. 257,833. (No model.)

To all whom it may concern:

Be it known that I, EDWARD T. POTTER, a citizen of the United States, residing at Newport, in the county of Newport and State of Rhode Island, have invented certain new and useful Improvements in Magic Lanterns, of which the following is a specification, reference being had to the drawings accompanying and forming a part of the same.

10 Heretofore the views or the advertising or similar text and whatever of the kind is to be projected on a screen by a magic lantern have been painted, photographed, or similarly portrayed on separate slides of glass, prepared 15 paper, or other translucent medium, of sizes which vary according to circumstances, and which must be successively inserted and withdrawn by an attendant. This is a somewhat laborious operation, requiring considerable 20 care, skill, and experience to produce a good effect; but the change of views by the substitution of plates produces an unpleasant effect upon the eye, which has heretofore been improved upon only by the employment of a 25 compound system of lenses in an instrument known as a "dissolving-view" lantern.

The object of my invention is to remedy this in a simple and economical way, and to render the operation continuous, so that a 30 panoramic picture or a long written or printed article or address may be shown on a screen by a magic lantern without breaks, and may without interruption in the text or picture be seen or read continuously, like a panorama or 35 an ordinary letter or column of print. To carry out this object I use with a magic lantern a continuous flexible band or strip, upon which the scenes, figures, or text to be reproduced are painted or otherwise portrayed. Any trans- 40 parent or translucent and flexible substance may be used for the band, such as paper, treated in well-known ways, or collodion or other cel- lulose compounds. Upon such a band I paint or in any suitable manner apply views of 45 whatever kind or character may be desired. I furnish a lantern with two or more reels or spools and wind off the band from one onto another, drawing the band through the beam of light in proper position with reference to 50 the lenses to project or reflect the views upon the screen.

By the expression "continuous strip" I mean to imply an extended strip or band capable of being rolled or wound up, on which a series of views or the text of an extended 55 article may be depicted, this in contradistinction to a short sheet, plate, or slide such as has commonly been employed.

In order to intensify and to vary the effect produced by a magic lantern, I also stamp or 60 punch out the letters and numbers, and sometimes parts of the figures and scenes, so as to permit the light-rays to pass through the perforations to the screen. In such cases, where the scenes on the screen are produced in part 65 or whole by the direct rays of light, it is obvious that an opaque material may be used for the band. The perforations forming any given character or figure may be connected, or may be a number of small perforations, as herein- 70 after described.

I employ as a means of impelling the band a clock mechanism or a source of power controlled by clock-work or its equivalent, so as to keep up a steady and even motion of the 75 band.

Referring to the drawings, Figure 1 is a perspective view of the entire apparatus with my improvement applied. Fig. 2 is a section of the flexible band, exhibiting the perforated 80 letters.

It will be understood that the invention is not restricted to any particular form of magic lantern, nor to any particular device or means for drawing the continuous band 85 through the same. So, therefore, in illustrating the nature of the invention I have selected a typical and convenient form of instrument, which embodies the principle and mode of operation merely of the improvement. 90

Let A represent the case of an ordinary magic lantern. B is the lens tube, and C a plate to which it is secured, and between which and the case A is a passage-way, through which the band D is drawn in either a vertical or horizontal direction.

For convenience, the box or case A is provided with the legs E, and under the box is mounted a reel or spool, F. The shaft of this spool is provided with means for turning it. 100 This may be an ordinary handle; but I prefer to use some form of motor, such as a train of

clock-work, one member or gear of which, G, is shown as supported in the frame H. The train gears with the shaft or with the wheel G.

A spool or reel, K, is mounted in bearings 5 above the case A. This spool carries the band, which is drawn off and reeled onto the lower spool, F, by the rotation of the latter.

In Fig. 2 a section of the band is shown, in which the letters are made by the lines of perforations. In a similar manner parts of any view or picture may be cut away to permit the passage of the rays of light through the paper. The particular manner of making these perforations is immaterial.

15 The band, which I have stated above may be of paper treated with any of the many well-known substances for rendering it transparent or translucent, is prepared or printed with the scenes or pictures or text, so that 20 the movement of the band will bring the same to view in proper order or succession. When a long article or address is to be shown, it will be advisable to print or prepare it in lines running across the band, so that it may be 25 presented by a vertical movement of the band. In this manner I may exhibit panoramas, addresses, operatic or dramatic scores, sermons, and the like.

What I claim as my invention is—

1. As a new article of manufacture, a magic- 30 lantern slide consisting of a continuous flexible strip or band of transparent or translucent material having views, figures, or text portrayed thereon.

2. A continuous flexible band or strip for 35 magic lanterns, having figures or text formed by perforations through the band or strip, as set forth.

3. The combination, with a magic lantern, 40 of reels or spools carrying a continuous band or strip of flexible transparent or translucent material upon which the views or figures are portrayed, the reels being placed in position to direct the band through the lantern, whereby an enlarged image will be projected by the 45 lantern, and a motor for drawing the band through the lantern from one reel to the other, as set forth.

Signed this 8th day of December, 1887.

EDWARD T. POTTER.
